CLAIM

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a rear perspective view showing the use state in which rear display part is operated, showing example displayed information;

FIG. 10 is a front perspective view in a condition that the claimed design has been opened completely;

FIG. 11 is a front view of FIG. 10;

FIG. 12 is a rear view of FIG. 10;

FIG. 13 is a left side view of FIG. 10;

FIG. 14 is a right side view of FIG. 10;

FIG. 15 is a top plan view of FIG. 10;

FIG. 16 is a bottom plan view of FIG. 10; and,

FIG. 17 is a rear perspective view of FIG. 10.

(Continued)

The broken lines depict portions of the mobile phone, and example displayed information in FIG. 9, that form no part of the claimed design.

1 Claim, 17 Drawing Sheets
